SHEET FEEDING APPARATUS

Cutler D. Knowlton, Beverly, Mass., assignor to
 Hoague-Sprague Corporation, Lynn, Mass., a
 corporation of Massachusetts

Application June 19, 1940, Serial No. 341,326

76 Claims. (Cl. 271—31)

This invention relates to a sheet feeding apparatus and is herein illustrated and described as embodied in a mechanism for feeding box and box cover blanks to an apparatus for operating on such blanks. The invention is not limited, however, to use in box making machinery but may be employed to equal advantage in any apparatus for receiving sheets and delivering them one at a time to operating means.

It is an object of the present invention to provide for the rapid and efficient handling of a number of packs of sheets of different sizes and to insure that they will be successively presented in proper position to a device which picks off the sheets one at a time and presents them to delivery means or other apparatus. Accordingly, the invention provides a conveyor mechanism upon which the blanks are supported on edge in groups or packs, these packs being held in spaced relation to one another on the conveyor until such time as they are inserted in a magazine at the delivering end of the conveyor. Spacing of the packs is accomplished by the provision of a number of pack supporting members which form a part of the conveyor mechanism and have the dual functions of separating the packs and of transmitting to the packs the movement of the conveyor mechanism toward the magazine. Provision is also made for shifting these pack engaging members from pack supporting position at or near the end of their movement toward the magazine, and for moving them into pack engaging position at the opposite end of the conveyor.

A further object of the invention is to insure the certain and rapid removal of successive single sheets from the magazine. Provision is therefore made for suction members adapted to bend or roll the bottom edge of the forward sheet in the magazine away from the stack therein. When the edge of the sheet has been so rolled away from the stack, a separator or shuttle moves upwardly to complete the separation of the sheet from the stack. This separator is provided with means for engaging the upper edge of the sheet, thereby enabling the separator, as it returns to its original position, to carry the sheet downwardly into a position where it may be engaged by delivery mechanism.

Another object of the invention is to control the feeding movement of the conveyor in such a manner that it will always maintain an adequate supply of sheets in the magazine from which the picking means removes single sheets. In accordance with this object, provision is made for advancing the conveyor at two different

speeds. The high speed conveyor advancing mechanism is arranged to operate only when there is a gap between the rearmost sheet in the magazine and the foremost sheet in the next succeeding pack which is about to be inserted in the magazine. The low speed conveyor advancing mechanism is controlled by the picker means in such a manner that when the picker means must advance into the magazine beyond a predetermined point in order to grip the leading sheet, the low speed conveyor advancing means is started and continues to operate until the supply of sheets in the magazine has been replenished.

A further object of the invention is to provide means whereby a predetermined number of sheets may be run through the machine, and upon the movement of the last sheet through the machine, the feeding mechanism will be rendered inoperative. To this end, there are provided a register for indicating the number of sheets that have passed through the machine and mechanism controlled by the register for shutting off the suction in the suction members after the requisite number of sheets have been fed thereby.

Obviously, it is desirable to produce an equal number of boxes and covers. For this reason the box making machinery and the cover making machinery are advantageously operated as two sections of a single unit. Consequently, there are two substantially identical feeder mechanisms, one for boxes and one for box covers, and it is, accordingly, a further object of the invention to provide means for insuring that the two feeding mechanisms will each feed the same number of box blanks and cover blanks. In the attainment of this object, I have provided mechanism for controlling the amount of suction in the suction members of the picking means in such a manner that if the suction member of one feeder picks up a blank but that of the other feeder fails to do so, the vacuum in the member holding the blank will be insufficient for the member to maintain its grip on the blank and it will thereupon release it.

Other features of the invention will appear upon consideration of the following specification and the appended drawings in which one form of my invention is described and illustrated.

In the drawings,

Fig. 1 is a side elevation of the pack advancing section of a machine embodying my invention;

Fig. 24 is a wiring diagram of the machine.

As has already been pointed out, the embodiment of the invention shown in the drawings for purposes of illustration is a feed mechanism for a box making machine. This machine being adapted to manufacture boxes and covers, there will, of course, be two feed units, one for the covers and one for the boxes. Inasmuch as these two feed units differ from each other only in certain particulars, which will hereinafter be pointed out, only one feed unit has been illustrated.

In order to aid in understanding the invention, the illustrated machine will be described generally first, and then the separate sections will be taken up in detail.

General description

Referring now to Figs. 1 and 2, the machine may be divided, roughly, into three sections,—a conveyor mechanism, generally designated at A, which holds on edge a number of separate packs of blanks X having corner laps L and end wings W (Figs. 15 and 16) and carries them to a magazine B; a picker mechanism, generally indicated at C, for separating a single sheet from the stack in the magazine; and a delivery mechanism D, which picks up the blank presented to it by the picker mechanism and carries it to the machine

where it is made into a box-part. The conveyor mechanism A comprises a framework 50 to which is secured a table 52 upon which the blanks rest between opposite guide-walls 54. Movement of the packs of blanks over the table toward the magazine B is effected by a number of vertical rods 56 which act as supports to hold the packs in upright position and keep them separate, these rods being slidably carried in conveyor chains 58. Upon arrival at the magazine, the rods are moved downwardly out of pack supporting position by lever mechanism 60 which simultaneously lifts rods at the opposite end of the conveyor into pack supporting position.

Situated on the opposite side of the magazine B from the conveyor mechanism is the picking mechanism C comprising a picker arm 62 mounted for swinging movement about a shaft 64 and carrying a presser foot 66 and suction cups 68. The actuating mechanism for the picker arm is such that the presser foot and the suction cups are moved toward the leading blank in the magazine in approximately heightwise alignment. As these members engage the leading blank, the suction cups become effective to grip the lower edge of the blank and then, while the main portion of the blank is held in place by the presser foot, to swing said edge forwardly away from the stack in the magazine. When the blank has been thus bent, a pair of shuttles or separators 70 move upwardly between it and the remainder of the stack to complete the removal from the magazine.

The shuttles are provided with catches 72 which engage the top edge of the blank and, when the shuttles return to their starting position, slide the blank downwardly between carrier wheels 74 and curved guides 76. The carrier wheels are provided with lugs 78 traveling in timed relation to the shuttles, so they will engage the upper edge of the blank to continue its advance. After having been carried through approximately a half revolution by the wheels, the blank enters between a second set of guides 80 and a set of sprocket wheels 82 driven by chains 84. These chains are provided with lugs 86 which engage the edge of the blank and carry it up over the wheels 82 and between hold-down bars 90 and parallel horizontal rails 88 along which it is advanced by the chains to the operating mechanisms of the machine.

Conveyor mechanism and magazine

Returning now to the conveyor section A of the machine, the table 52 is divided into three parts, a center section 92 (Fig. 3) and opposite side sections 94, 94. Adjacent to the outer edges of the side sections 94 there are provided a series of brackets 96 to which angle irons 100 are secured by screw-and-slot connections 98. The guide-walls 54 are fastened to the vertical portions of these angle irons, so that by loosening the connections 98 they may be adjusted to the correct relation to each other and to the magazine B. To the forward end of each of the walls 54 is secured an upstanding support 102 and to this support, as shown in Fig. 7, is fastened a centering finger 104. This centering finger, which is preferably of a somewhat resilient metal, is inclined toward the center section 92 of the table, extending inwardly slightly beyond the inner face of the wall so that it exerts pressure upon the blanks and positions them transversely as they enter the magazine.

The magazine B is provided with means for holding the blanks in upright position parallel to one another in proper relation to the picking mechanism. To this end, dogs 106 (Figs. 1, 2 and 5) are provided at the top and bottom of the magazine. The forward faces 107 of these dogs are flat and provide a surface against which the blanks are urged at their top edges by a hooked end 108 of a leaf spring 110 bolted to a bridge bar 112 secured to uprights 113 of the frame. At the bottom edges of the blanks, there is a retaining member 114 secured to a rod 116 5 slidable longitudinally of the table in a boss 118. This retaining member is movable in a slot in the table and is urged rearwardly by a spring 120 surrounding the rod, thus holding the pack of blanks in the magazine tightly against the dogs 106. Forward displacement of the blanks at their top edges is limited by stops 130 on blocks 132 adjustably fastened to the frame by screw-and slot connections 134. The stops, the end of the spring 110, the retaining member 114, and the dogs 106 co-operate to hold the blanks upright in the magazine, close against one another, in a predetermined relation to the picking mechanism C.

To permit the blanks to be fed into the magazine, the dogs 106 have their rearward faces beveled at 121 (Fig. 5) and are pivoted at 122 in blocks 124 adjustably secured to a crossbar 125 of the frame by screw-and-slot connections 126. The dogs are urged into the path of the blanks by spring-pressed pins 128 and thus, when a stack of blanks is being moved forwardly into the magazine, the dogs will be forced aside by their upper and lower edges, and when the entire pack has been fed into the magazine, the dogs will drop down and prevent the blanks in the magazine from falling rearwardly.

Between the rods 56 of the conveyor mechanism, the operator may insert separate packs of box-blanks of any given number in one section 94 of the machine and like packs of cover blanks in the other section. If a number of orders of different magnitudes are being filled, this arrangement facilitates the handling of the packs of blanks, enabling them to be inserted in the machine and kept separate for the operations upon them. The rods of each section travel in pairs under the influence of the chains 58. At regular intervals along these chains there are special guide links 136 (Figs. 3 and 10) through which the rods may be slid longitudinally without disturbing the movement of the chains. These chains operate in pairs, one pair on each side of the center section of the table. The two chains of each pair are positioned one above the other, with the links 136 in vertical alignment so the rods 56 will be held substantially vertical. At the forward or magazine end of the conveyor the chains pass over sprocket gears 138 which are secured to a vertical shaft 140 journaled in the frame. At the rear end of the conveyor the chains pass over similar sprockets 142 secured to short shafts 144 journaled in bearings 146 formed in blocks 148 secured to uprights 149 of the frame by screw-and-slot connections 150. By loosening these connections, the blocks may be shifted horizontally to regulate the tension on the chains. Rotation of the shaft 140 and sprocket gears 138 and 142 will cause the chains to carry the rods 56 toward and away from the magazine, the inner runs adjacent to the center section 92 of the table traveling toward the magazine.

To hold the slidable rods in an upper or pack-separating position, a rail 152 is secured to the frame beneath the inner runs of the chains. A base 154 (Fig. 10) is threaded onto the lower end of each rod and secured by a nut 156. Thus, a rod moving toward the magazine is held in pack supporting position by the rail 152.

As each rod reaches the magazine, it is moved out of pack separating position for its return to the loading end of the conveyor. This is accomplished by causing the rod to be lowered until its top is below the table 52. Since the rail 152 is directly beneath the inner run of the chain, as the chain reaches the sprocket 138 and begins to move about it, the rod will be carried off the rail, where it is free to drop under its own weight, in a direction substantially parallel to the rear face of the sheets in the magazine B, to a lower rail 158, along which it may travel back to the loading end of the conveyor in lowered position. It may sometimes occur that the pressure of the pack of blanks against the rods is sufficient so the rods will not drop by gravity. To insure that the rods will be fully retracted and not strike the guideways 54, there is provided the lever 60 (Figs. 1, 3 and 4) which is pivoted approximately at the center of the machine on a shaft 160 journaled in uprights 162 bolted at 164 to the frame. At the magazine end 166 of the lever are two links 168 (Fig. 10) pivoted on a cross pin 170 carried by the lever. The other end of each link is connected by a pin 172 to a slide 174, movable vertically on a rod 176 secured to the frame. At the lower end of the slide is a threaded stud 178 to which a finger 182 is secured by a nut 180 and beneath the end of which the rod-bases 154 travel. Movement of the lever 60 is so timed relative to the movement of the chain that as the rod is shifted off the rail 152, and the end 166 of the lever is swung downwardly, the finger engages the base and forces the rod down to the level of the lower rail 158.

As each of the rods 56 reaches the rear or loading end of the conveyor, it must be raised from the lower rail 158 to pack engaging position on the upper rail 152. To accomplish this, the lever 60 has at its rearward end 184 two links 186 (Figs. 1 and 4) pivoted to it by a cross pin 188. The other end of each link 186 is pivoted 50 to a slide 190 movable on a vertical rod 192 secured in the frame. To the lower end of the slide 190 is secured a table 194 above which the base of the rod 56 is moved as said rod begins its travel about the sprockets 142. With the rod 55 above the table, the lever 60 is swung about the shaft 160 by mechanism, hereinafter to be described, so as to lift the rod into a position such that as it travels about the sprockets 142 it will move onto the rail 152. The rods are thus successively raised and lowered for their pack-advancing travel and idle return movement.

The chains 58 are driven by worm gears 196 (Figs. 1 and 4) secured to the lower ends of the vertical shafts 140. The worm gears mesh with worms 198 fast on a shaft 200 journaled in the frame and having secured thereto a sprocket gear 202 over which passes a drive chain 204. This chain also passes over two other sprockets 206 and 208 and a tightening idler gear 210 journaled on a spindle 212 carried in a slot 214 in a boss 216 on the frame. Adjustment of the tension of the chain 204 is effected by loosening a nut 213 threaded on the end of the spindle 212, thus enabling the spindle 212 to be shifted in the slot 214.

Swing movement of the lever 60 is effected through a crank wheel 230 fast upon a shaft 232 and linked to the lever by a connecting rod 229. This rod comprises an end member 222 pivotally connected to ears 224 on the under side of the lever, the rod being threaded into the end member 222 so that the length of said rod may be adjusted and held in position by a nut 228. The end 226 of the connecting rod is pivoted to the crank wheel 230, which is mounted on a shaft 232, and has secured to it a pair of drive members 234. At the opposite sides of each drive member are slots 236 adapted to receive one of two pairs of rolls 238 projecting oppositely from the chain 204. It will be noted that as the chain 204 travels from the sprocket 298 to the sprocket 206 it passes over a roll 239 which is secured to the shaft 232 between the drive members 234. This roll 239 so guides the rolls 238 that they will be carried into the slots 236 and cause the crank wheel 230 to rotate contraclockwise (Fig. 1). After half a revolution of the crank wheel has raised the end 184 of the lever 60, the rolls are at the top of the guide roll 239 in position to leave the slots 236.

To insure that the crank wheel will stop in proper positions for the rolls to enter and leave the slots in the drive member, a spring-pressed detent pin 240 is mounted on the upright 162 adjacent to the crank wheel. When the pin is in a notch 242 in the periphery of the crank wheel, the lever is at either the top or the bottom of its movement and the slots 236 are in vertical alinement with one another so that the rolls may readily enter or leave the slots.

The ratios of the various gears and sprockets are such that the chain 204 makes one complete revolution during the period that the chains 58 travel a distance equal to the space between two adjacent rods 56. Thus, as the next rod approaches its elevating position, the end 184 of the lever 60 will be swung down to its receiving position. The rod-shifting movement of the lever occurs shortly after the rod at the magazine has moved off the rail 152 and the rod at the loading end of the conveyor has moved over the table 194. The return movement of the lever will occur when the chains 58 have traveled approximately half the distance between rods. There is thus allowed the proper time for the chains 58 to carry the rod at the magazine end onto the rail 153 and to carry the rod at the loading end of the conveyor onto the rail 152, and for the lever-ends 166 and 184 to return to their starting positions. Therefore, as the next rod at the magazine end moves off the rail 152, the finger 182 will be above the base of the rod in position to force it downwardly. Similarly, the table 194 will be in elevating position below the base of the rod at that end of the conveyor.

Driving of the conveyor and of the lever is effected through a sprocket 243 (Figs. 1 and 5) mounted on a shaft 244 upon which the sprocket 208 is secured. A chain 246 passes over the sprocket 208 and over a sprocket 248 keyed to a shaft 250 connected to a reduction gearing 252. Power to operate the reduction gearing is supplied by a pair of motors 254, 256 respectively, in a manner hereinafter to be described.

Picker mechanism

The blanks having been brought to the magazine and inserted therein in a horizontal stack, i. e., on edge with their side faces substantially vertical, they are removed from the magazine B

one at a time and presented to the delivery means by the picker mechanism C illustrated in Figs. 2, 11, and 12. Secured to the uprights 113 of the frame is a horizontal crossbar 258 to which hangers 260 are bolted, these furnishing bearings for the shaft 64. Rotatable about the shaft is a sleeve 262 and to this sleeve the picker arm 62 is clamped at 264. To the picker arm the presser foot 66 is pivotally connected at 266. The presser foot has an extension 268 in which a pipe 270 is clamped at 272. The suction cups 68 are clamped to the ends of the pipe on either side of the presser foot, passageways 274 in cup mountings 275 connecting the cups to the pipe. An arm 276 is clamped at 280 to the shaft 64 by a bolt 278, the other end of the arm being pivotally connected to a link 282. The link is pivotally connected at 284 to a yoke 286 upon the presser foot extension 268. By this arrangement relative movement of the sleeve 262 and the shaft 64 causes the presser foot and the suction cups to swing about the axis of the pivot 266.

To effect such relative movement an arm 288 is secured to the end of the shaft 64, this arm being connected by a link 290 to a bell crank lever 292 (Figs. 2, 6 and 14) pivoted on a pin 294 journaled in a bearing member 296 secured to a bar 298 of the frame. An arm of the bell crank carries a roll 300 which rides in a cam groove 302 in the side of a gear 304 keyed to a shaft 306 journaled in the frame, and driven through connections (not shown) to a motor 307 (Fig. 24).

A similar arrangement is provided for the sleeve 262. This mechanism comprises an arm 308 fastened to the sleeve 262 and pivotally connected to a link 310. The opposite end of the link extends through a boring in a connecting pin 312 (Figs. 6 and 13) turning in a forked arm 314 of a bell crank 316. A shoulder 318 is formed on the rod 310 and a spring 320 surrounding the rod between the shoulder and the pin provides a yieldable connection between the rod and the bell crank, so that if the presser foot 66 strikes the pack of blanks in the magazine before the arm of the bell crank has completed its rearward movement toward the magazine the rest of the movement will be taken up by the spring. A nut 322 threaded onto the end of the rod 310 assures that the bell crank will pull the link rearwardly upon return to its initial position. The bell crank is pivoted at 324 to a bracket 326 secured to a crossbar 328 of the frame and carries on its other arm 330 a cam roll 332. This cam roll operates in a cam groove 334 cut in the side of a disk 336 secured to the shaft 306 by a key 338, and providing operating mechanism by which the picker arm 62 is swung toward and from the magazine. The configuration of the cams 334 and 302 is such that the presser foot 66 and the suction cups 68 are swung in toward the magazine in substantially heightwise alinement, that is, in the position shown in Fig. 2. When they have made contact with a blank, the suction cups are caused to grip the bottom edge and pull it forward over the edge of the retaining member 114 to the position shown in Fig. 11. As the lower edge of the blank is rolled outwardly, it is also drawn downwardly away from the hook 108, so that it is free to be moved away from the remainder of the pack by the separator 70.

To create suction in the cups 68, one end of the pipe 270 is connected by a flexible hose 340 (Figs. 2 and 24) to one side of a manually operated shut-off valve 342. The opposite side of this valve is connected through a cam-actuated piston

valve 344 (Fig. 13) to a suction pump (not shown). The piston valve 344 comprises a cylinder in which a piston 346 is slidable and is so arranged that in its upmost position the suction valve is closed. The piston is pivotally connected to a link 348, the opposite end of which is slotted to receive a bolt 350 by which it is adjustably connected to a lever 352 pivoted in an ear 354 on the frame of the machine. The opposite end of the lever 352 carries a cam roll 356 which is held against a cam surface 358 of the cam disk 336 by a spring 359. This cam surface is so shaped at 360 that the valve 344 is opened as the suction cups engaged the forward blank in the magazine and then, as the cups are swung away, the valve is partially closed.

As has been pointed out, the machine is built in two parts, one for boxes and one for box covers. The mechanism for opening and closing the air suction valve is common to both parts, the suction cups of each being connected to the valve 344 on the side away from the suction pump, as shown in Fig. 24. The reduction in the suction by partial closure of the valve is such that unless the suction cups of both sides of the machine have gripped the blanks, the leakage at the pair which failed will be so great that those on the other side of the machine will not retain sufficient vacuum to hold the sheet. By this arrangement, it is made certain that an equal number of box and cover blanks will be fed.

To complete the separation of each blank from the stack and to move it out of the magazine, the separators 70 are provided. These separators, two in number in the illustrated machine, are secured to laterally extending rods 362 (Fig. 2) which at their ends are fastened to slides 364. The slides are movable vertically upon rods 366 held by set screws 368 in collars 370 bolted to the frame. The movement of the slides is effected through a lever 372 pivoted at 374 in a frame-bracket 376. The forked end 378 of the lever is pivotally connected to the end 380 of a link 382, the length of which is adjustable. The opposite end of the link is pivoted to an ear 384 upon one of the slides 364. Movement of the lever 372 is accomplished through a crank 386 linked by a connecting rod 388 to the lever at 390. The crank 386 is keyed to a shaft 392 journaled in a bracket 394 secured to the frame. This shaft 392 is driven by a gear 396 which meshes with the gear 340 on the shaft 306. The ratio of the gears 396 and 340 is 1 to 2 so that the lever 372 reciprocates the separators twice during a single revolution of the shaft 306, the cams 302, 334, and 358 being so formed as to cause the picker mechanism to perform two complete cycles for each revolution of the cams.

As the separators travel upwardly, their upper ends, which are slightly pointed to enable them to separate the leading blank from the pack in the magazine, complete the separating action begun by the presser foot and the suction cups and move the blank to the position shown in Fig. 11 in dotted lines for presentation to the delivery means. Each separator is provided with the catch 72 formed on one end of a member 400 pivoted at 398 in the separator and projecting outwardly to engage the edge of the sheet. Forward movement of the catch 72 is limited by a lug 402 which strikes against the inside of the hollow end of the separator. A spring 404 between the separator and a lug 406 on the member 400 holds the catch in sheet engaging position but permits it to be forced inwardly as the sepa-

rator moves upwardly and the catch strikes the rear face of the blank being separated from the stack. With the face of the catch 72 in engagement with the top edge of the blank, the separator is ready for its return movement to carry the blank to the delivery means, a number of guides 408 secured to the frame being provided to hold the blank in position to be engaged by the catch.

To aid the separator in separating the leading blank from the stack on the box side of the machine, there are provided bridge bars 410 (Figs. 15 and 16) which connect the upper end of the separator and the rod 362 and thus prevent the ends of the blank, if they are warped forwardly, from catching on the rod 362 and thus causing the machine to jam. Further to assist in preventing the blanks from jamming, the end wings W of the box blanks X are inclined slightly rearwardly by stops 412 secured to the frame and against which they are pressed by the conveyor mechanism. When the leading blank is slid downwardly slightly by the rolling action of the suction cups and the presser member, the corner lap L of the leading box blank will not catch on the edge of the end wing W of the next succeeding blank as might be the case were the end wings not thus bent.

Delivery mechanism

To carry the blank from the picker to the operating means of the machine, the delivery mechanism is provided. Presentation of the blank to the delivery mechanism is effected by the downward movement of the separators 70. As the blank moves downwardly, its lower edge slides between the carrier wheels 74 and the arcuate guide bars 76 (Figs. 2 and 6). The wheels 74 are keyed to a shaft 416 journaled in the cross-bar 298 of the frame and driven by a gear 414 meshing with the gear 304. Support for the guide bars 76 is provided by a bracket 418 bolted to an upstanding lug 420 of a crossbar 422 of the frame. Rods 424 secured in the bracket 418 extend through the guide bars which are held in place thereon by set screws 426 (Fig. 2). As the shuttle continues its downward movement, the blank is carried to a position where its top edge may be engaged by the lugs 78 of wheels 74. End guides 428 secured to the rods 424 insure that the blank will not move endwise as it travels about the carrier wheels 74. After the blank has completed approximately half a revolution on the carrier wheels 74, its top edge is engaged by the lower ends 430 of the guide bars 80. These guide bars 55 are mounted on rods 432 secured to the frame by a hanger 434, the central portion 436 (Fig. 21) of which serves as a supplementary guide to prevent the central portion of the blank from buckling outwardly away from the shaft 306 as it passes over the wheels.

As the stripping of the blank from the carrier wheels 74 nears completion, its lower edge is engaged by the lugs 86 carried on the chains 84. These lugs carry the blank about the carrier wheels 82 and up onto the rails 88. The chains 84 pass over sprocket wheels 438 keyed to the shaft 308, these wheels being of slightly smaller diameter than the carrier wheels 82 to insure that the lubricant on the chains 84 will not get onto the blank being fed. The blank is now in position to be carried between the rails 88 and the hold-downs 90, to the operating mechanism of the machine. The rearward ends of the rails are provided with fingers 440 (Fig. 21) which 75 separate the blank from the carrier wheels 82,

Conveyor driving mechanism

The normal rate of advance of the blanks into the magazine is preferably only slightly faster than the rate at which they are withdrawn by the picker mechanism. In order to close the gaps between the packs of blanks as they are about to be fed into the magazine B, the conveyor must be advanced somewhat more rapidly. To meet these requirements, it is necessary to operate the conveyor at two different rates of speed and for this purpose the motors 254 and 256 are provided, the motor 256 being arranged to drive the conveyor at a slow rate of speed and the motor 254 at a higher rate. Referring now to Figs. 8 and 9, the slow speed motor 256 is provided with a pulley 442 secured to a motor shaft 444 and arranged to drive a belt 446 which passes over another pulley 448. The pulley 448 is of substantially larger diameter than the pulley 442 and is mounted on ball bearings 450 for free rotation about a bushing 452 keyed to a motor shaft 454 of the high speed motor. Rings 456 carried by ball-bearing raceways 458 hold the pulley 448 in position laterally. The bushing 452 is provided with a flange 460 on its inner end and is threaded at its outer end to receive a nut 462 which holds a clutch plate 464 in position on the shaft. A locking washer 466 is provided for the nut 462.

Secured to the periphery of the clutch plate 464 by screws 468 is a pawl carrier 470 having a number of pairs of ribs 472 upon its side face. These ribs form guideways for pawls 474 which are urged inwardly toward the axis of the shaft 454 by springs 476 and are provided with teeth 478 which, when the mechanism is at rest, engage teeth 480 of a clutch ring gear 482 secured to the pulley 448 by screws 484. By this arrangement, when the slow speed motor is running, it drives the large pulley 448, and the clutch ring gear 482, and the pawls 474 carried by the clutch plate 464 drive the motor shaft 454 which is connected to the reduction gear 252. When the high speed motor 254 is in operation, however, and this may occur regardless of whether or not the slow speed motor 256 is running, the clutch plate 464 is rotated at a much more rapid rate than it would be if driven by the pulley 448. This relatively high speed sets up a centrifugal force which causes the pawls 474 to move outwardly against the springs 476, thus disengaging the pulley 448 driven by the slow speed motor 256. When the high speed motor shuts off, the clutch plate decelerates until its speed is equal to that of the pulley 448, at which time the springs 476 overcome the decreased centrifugal force and move the pawls into engagement with the clutch gear teeth 480.

To start the high speed motor 254, when there is a space between the foremost blank of the pack about to be fed into the magazine B and the rearmost blank in the magazine, a gap detector is provided. This comprises a spring finger 486 (Figs. 2 and 5) secured to a portion of the cross bar 125 and depending in the path of the advancing blanks to such a distance that it will be raised by the pack of blanks being fed into the magazine. The finger is provided with a horizontal portion 488 which engages a push button 490 of a switch 492 connected to the high speed motor. This switch is so arranged that pressure upon the push button opens the switch, thereby shutting off the high speed motor 254. Upon release of the button, the switch closes, and when the finger is freed by the blanks, the high

speed motor is started and continues to operate until the conveyor has closed the gap behind the magazine and again raised the finger.

Mechanism is also provided for intermittently operating the low speed motor 256 of either the box section or cover section. To this end, a mercury switch 494 (Figs. 17 and 18) is mounted on a block 495 pivoted on a screw 496 for tilting movement in a switch box 498 secured to the frame. At the rear of the switch box a rod 502 is movable in a guide 500. The lower end of this rod carries a pin 504 on which is pivoted a lever 506 held in place by a spring 508 and a nut 510. Each end of the lever is secured to one of a pair of switch rods 512, 513 which extend upwardly and are slidable in eyes 514 on the switch block 495. The rods are each provided with heads 516 so that when both heads are in contact with the eyes upward movement of either one of the switch rods operates the lever 506, lowering the opposite switch rod and tilting the switch 494 to open or closed position. The switch is held in the position to which it is moved by a spring-pressed pin 517 carried in a bore in the block 495.

Control of the switch is effected by positioning the switch rods 512, 513 directly over the link 310 connecting the picker arm sleeve 262 to its operating cam 334 (Figs. 2 and 13). The link 310 is provided with a pair of collars 518, 519 which are clamped thereto with screws 520. Blocks 522 and 523 are respectively pivoted at 524 to the collars 518, 519 and are held in normal position by springs 526. If because of improper timing the link 310 moves forwardly or rearwardly in such a manner that one of the blocks strikes one of the switch rods 512, it will simply tip and will not cause damage.

In order to cause the slide rod 502 to reciprocate vertically, it is connected by a yieldable link arrangement 527 to one end of a lever 528 pivoted in an ear 530 secured to the frame, the other end of the lever being connected to an arm 532 carrying a cam roll 534 (Figs. 6 and 13) on its opposite end. The cam roll is held in engagement with a cam surface 536 on the cam disk 336 by a spring 538 (Fig. 2) connecting the lever 528 and a pin 540 on the frame of the machine. The cam surface 536 is so related to the picker actuating cams 302, 334 that it causes the switch mechanism to move downwardly and to return while the presser foot 66 and the suction cups 68 are in engagement with the forward blank in the magazine. If there is an adequate supply of blanks in the magazine, the switch 494 will remain in the position shown in Fig. 17. That is, the switch rod 513 will strike the block 523 and will not move the switch 494 out of its open position. If, however, the picker mechanism is compelled to reach rearwardly a greater distance into the magazine in order to grip a blank, the link 310 will bring the block 522 into position underneath the switch rod 512. When the cam surface 536 causes the slide rod 502 to move downwardly, the switch rod 512 strikes the block 522 and tips the switch, thus closing the circuit and setting the slow speed motor in operation. The switch will remain in this position until the picker mechanism moves rearwardly to grip a blank such a short distance that the block 523 is brought into position beneath the switch rod 513, thus opening the circuit.

Control devices

To stop the machine in case of jams caused by the deviation of a box blank from its proper

line of travel, there are provided two control devices. Referring to Figs. 19 and 20 the first of these devices is operated by the gear 396 on the shaft 392, which drives the shuttle operating lever 372, and comprises a bushing 542 keyed to the shaft and having formed integral with it a plate or flange 544. This plate is provided with a shouldered portion 546 on which is mounted a ring 548. The ring has secured to it a number of pins 550 each surrounded by a spring 552 acting between a recess 554 in the plate 544 and a washer 556 secured on the end of the pin. The spring thus holds the ring 548 close against the plate 544 but permits it to be moved away from the plate when the pin 550 is pressed. Separation of the ring 548 and the plate 544 is accomplished by a number of rivet heads 558 which are secured in a recess 560 in the gear 396. By this arrangement, if the gear 396 rotates relatively to the plate 544, the rivet heads 558 strike the rounded ends of the pins 550 and cause them to push the ring 548 away from the plate 544. As the ring 548 moves away from the plate 544, it strikes a roll 562 carried by the arm 564 of a switch 566 normally held in closed position by a spring 568, and opens the switch.

Movement of the ring 548 axially of the shaft 392 may occur only when there is relative rotary movement between the plate 544 and the gear 396. These parts are normally held against rotation by a shear pin 570 which extends through a sleeve 572 in the gear 396 and into a bore in the plate 544. A pin 574 holds the shear pin in place. The shear pin 570 is provided with a neck 576 which is of smaller diameter than the main portion and which is positioned on the line at which the plate 544 and the gear 396 meet. Thus, if the shuttle in its upward movement meets a twisted blank which resists its movement, the shear pin will be broken before any of the other parts of the machine are strained sufficiently to cause them injury. Breakage of the shear pin 570 will cause the gear 396 to rotate relatively to the plate 544, thus opening and closing the switch 566 each time one of the rivet heads 558 strikes the rounded head of one of the pins 550.

It may sometimes occur that a blank in either magazine will be moved upwardly out of its proper line of travel as the shuttle 70 rises. In order to prevent damage it is necessary to provide a mechanism which will stop the machine when this occurs. To this end, a jam detector finger 578 (Figs. 2 and 23) is pivoted on a bracket 580 secured to a plate 582 bolted to the crossbar 112 of the frame. One end of a link 584 is pivotally connected to the detector finger, the opposite end thereof passing through the end of one arm 586 of a bell crank lever common to the two magazines and pivoted on a projection 588 of the plate 582. Springs 590 surrounding the link 584 between the arm 586 of the bell crank lever and washers 592 provide a yieldable connection between the link and the lever arm. The other arm 594 of the bell crank lever extends over the crossbar 112 of the frame and rests on the button 596 of a switch 598 which is so arranged that pressure on the button opens the switch. By this arrangement, if a blank jams and is forced upwardly into the position shown in broken lines in Fig. 23, it strikes the jam detector finger 578 and through the bell crank lever, opens the switch 598.

It is desirable that when the switch 598 of the jam detector or the switch 566 of the shear pin arrangement is open, the entire machine should

be stopped. To this end, the control system diagrammed in Fig. 24 is provided. This system comprises an electrically operated switch 600 for controlling the main driving motor 307, a starting circuit 602 for completing the circuit for the winding 604 of the main switch, and a holding circuit 606 which is arranged to be closed by the main switch and to be broken by the switch 598 of the jam detector finger 578 or by the switch 566 of the shear pin mechanism. Starting and stopping switches 608, 609 respectively, and an emergency stop switch 610 are also provided in the holding and starting circuits. The main driving motor 307 is operated on 550 volts whereas the conveyor motors 254 and 256 are operated on a smaller voltage. Since it is desirable to stop the conveyor motors when the main driving motor is stopped by one of the safety devices, a relay 612 is provided. This relay is controlled by the main driving motor circuit and is so arranged that when that circuit is closed, the circuits to the conveyor motors are also closed, but opening of the main driving motor circuit will cause the conveyor motor circuits to be opened also.

By the arrangement outlined above, closing the starting switch 608 closes the starting circuit 602 and energizes the winding 604 to close the main switch 600 and therefore the holding circuit 606 for said main switch after the starting button has been released. Depression of the stop button or the momentary opening of any of the switches 566, 598, or 610 will, however, break the holding circuit and thus cause the main switch to be opened. Opening or closing of the main switch 600 which controls the main motor circuit will operate the relay 612 and open or close the circuits to the conveyor motors 254 and 256.

It will frequently be found desirable to stop the production of boxes without action by the operator after a predetermined number of blanks have passed through the machine. This may conveniently be done by shutting off the suction of the suction cups 68. To this end, there is provided a valve 614 (Fig. 22) which has a vertically slidable piston 616. The upper end of the piston is connected to the core 618 of a solenoid 620 connected to an indicator mechanism 622 of the type disclosed in Letters Patent of the United States No. 2,040,027, granted May 5, 1936, on the application of Frank E. Northrop. The indicator 622 is provided with two sets of indicator disks, one set 624 being arranged so that it may be set in accordance with the number of boxes which it is desired to produce, before the machine is stopped. The other set 626 is arranged to indicate the number of blanks that have been taken out of the magazine by the picker and is actuated by an indicator arm 628 connected by a rod 630 to an arm 632 secured to the picker arm shaft 64. Thus, every time this shaft rotates to swing the picker arm forward and cause a blank to be gripped, the indicator arm 628 is moved, thereby actuating the indicator disks 626. When the two sets of disks 624, 626 coincide, they open a switch in the indicator 622 through which the circuit 634 for the winding of the solenoid 620 passes, thus causing the solenoid to release the core 618 and close the slide valve 614. The machine will then continue to run but the picker mechanism will not remove any more blanks from the magazine until the indicator mechanism has been reset. The solenoid circuit 634 receives current through the con-

tacts of the relay 612 controlling the conveyor motors, and when the relay 612 opens the latter circuits, it also opens the solenoid circuit 634, shutting off suction at the valve 614.

Operation

Inasmuch as the function of each of the various portions of the machine has been described in detail in connection with the description of its mechanisms, only a brief description of the operation of the machine is believed to be necessary. The packs of blanks which may, of course, be of different sizes are placed between the pack supporting rods 56 of the conveyor with their edges resting on the table 52, and are moved by said rods into the magazine B. As each pair of rods reaches the magazine, it is lowered out of pack separating position by the lever 60, another pair of rods being raised simultaneously at the loading end of the conveyor. The picker mechanism then swings rearwardly, and with the presser foot 66 resting against the forward face of the leading blank in the magazine to hold it in place, the suction cups 68 grip the lower edge of the blank and roll it forwardly over the retaining member 114. If the pair of suction cups on one side of the machine fails to grip the blank at this point, the reduction in the amount of suction caused by the partial closing of the cam-actuated suction valve 344 will prevent the suction cups of the other side of the machine from pulling a blank from the magazine, thus insuring that an equal number of boxes and box covers will be fed to the operating mechanisms. With the blank in this condition, and with its upper edge pulled downwardly slightly out of engagement with the stop 130, the separators 70 are raised to complete the separation of the blank from its pack. If, in their upward movement the separators strike a broken or distorted blank which interferes with upward movement, the shear pin 570 breaks, opening the switch 566, and stopping the machine. Similarly, if a blank catches on one of the separators and is forced upwardly out of its normal path, it strikes the jam detector finger 578, opening the switch 598 and stopping the machine. At the top of the stroke of the separators 70, the catches 72 slip over the top edge of the blank, and on the return movement of the separators, the blank is slid downwardly between the carrier wheels 74 and the guides 76. A pair of lugs 78 moves the blank about the carrier wheels and between the guides 80 and the carrier wheels 82 in position to be engaged by the lugs 86 of the chains 84 which carry it upwardly and onto the rails 88. This operation is repeated with successive blanks until the switch in the indicator 622 is opened by the passage of the desired number of blanks through the machine, thus shutting off the suction in the suction cups 68.

Having thus described the invention, what I claim as new and desire to secure by Letters Patent of the United States is:

1. In a sheet feeding apparatus, a magazine, an endless chain having a path of movement toward and away from said magazine, a plurality of rods carried by said chain and movable longitudinally of themselves in said chain, means for supporting said rods in pack supporting position during their movement toward the magazine, and means for shifting said rods out of pack supporting position at the end of their movement toward said magazine.

2. In a sheet feeding apparatus, a pair of con-

veyor chains positioned one above the other, a plurality of rods carried by said chains and movable lengthwise of themselves in said chains, and means for moving said rods lengthwise of themselves at one end of said chains.

3. In a sheet feeding apparatus, conveyor means including a pair of endless chains positioned one above the other, a plurality of rods slidably carried by said chains for heightwise movement therein and constructed and arranged to hold a number of packs of sheets in spaced relation to one another, means for raising said rods to pack engaging position at one end of the conveyor, and means for lowering said rods out of pack engaging position at the other end of said conveyor.

4. In a sheet feeding apparatus, a sheet magazine, a pair of endless chains positioned one above the other, said chains having a path of movement toward and away from said sheet magazine, a plurality of rods slidably carried by said chains for heightwise movement therein, a high track along which said rods may slide toward the magazine when in raised position, a low track along which said rods may slide away from the magazine when in lowered position, means for raising said rods at the loading end of said chains, and means for lowering said rods at the magazine end of said chains.

5. In a sheet feeding apparatus, conveyor means, means for holding a plurality of packs of sheets on edge in spaced relation to one another on said conveyor means, and means including a lever for retracting said holding means from pack holding position.

6. In a sheet feeding apparatus, conveyor means including a plurality of members for holding a number of packs of sheets on edge in spaced relation to one another, a lever, means for rocking said lever about its fulcrum point, means carried by one end of said lever for raising one of said holding members into pack supporting position, and means carried by the other end of said lever for forcing one of said holding members out of pack supporting position.

7. In a sheet feeding apparatus, conveyor means including a plurality of retractable pack engaging members, said members being constructed and arranged to hold a number of packs of sheets on edge in spaced relation to one another, means including a lever for simultaneously moving one of said pack engaging members into pack engaging position at one end of said conveyor and moving another of said pack engaging members out of pack engaging position at the other end of said conveyor, and means for driving said conveyor means and for moving the pack engaging members in timed relation to one another.

8. In a sheet feeding apparatus, conveyor means including a plurality of retractable pack engaging members, said members being constructed and arranged to hold a number of packs of sheets on edge in spaced relation to one another, means including a lever for moving one of said pack engaging members out of pack engaging position at one end of said conveyor, a crank for operating said lever, and means for driving said crank in timed relation to the movement of said conveyor.

9. In a sheet feeding apparatus, conveyor means including a plurality of retractable pack engaging members constructed and arranged to hold a number of packs of sheets on edge in spaced relation to one another, a sheet magazine, means

for advancing said conveyor means to replenish the supply of sheets in said magazine, and separate means for advancing said conveyor means at a greater rate of speed to close the gaps between successive packs of sheets as they are about to be carried into the magazine.

10. In a sheet feeding apparatus, means for advancing a number of packs of sheets to a delivery point in spaced relation to one another, and means for increasing the rate of advance of said packs as each pack nears said delivery point thereby to close the spaces between said packs.

11. In a sheet feeding apparatus, means including a plurality of retractable pack separating members for conveying a number of separate packs to a delivery point, and means for advancing said conveyor means at a relatively high rate of speed as each pack nears said delivery point thereby to close the spaces between said packs.

12. In a sheet feeding apparatus, conveyor means including a plurality of retractable pack engaging members constructed and arranged to support a number of separate packs of sheets on edge in spaced relation to one another, a sheet magazine, means for picking successive sheets from said magazine, and means controlled by said picking means for advancing the conveyor means to replenish the supply of sheets in the magazine.

13. In a sheet feeding apparatus, a magazine, conveyor means constructed and arranged to carry to the magazine a number of packs of sheets in spaced relation to one another, means for picking successive sheets from said magazine, means controlled by said picking means for advancing said conveyor means, and means operative when there is a gap between the rearmost blank in the magazine and the foremost blank of the next succeeding pack to advance said conveyor means at a higher rate of speed.

14. In a sheet feeding apparatus, conveyor means constructed and arranged to carry to a magazine a number of packs of sheets in spaced relation to one another, means for picking successive sheets from said magazine, means adjacent to said magazine for detecting gaps between the rearmost blank in the magazine and the adjoining pack of sheets, and means controlled by said detector means for advancing said conveyor.

15. In a sheet feeding apparatus, means for advancing a plurality of packs of sheets in spaced relation to one another to a delivery point, a finger for detecting spaces between said packs at said delivery point, and means controlled by said finger for setting said advancing means in operation.

16. In a sheet feeding apparatus, conveyor means constructed and arranged to carry to a magazine a number of packs of sheets in spaced relation to one another, means oscillatable toward and away from said magazine for picking successive sheets from said magazine, and means controlled by the extent of oscillatory movement of said picking means for advancing said conveyor means.

17. In a sheet feeding apparatus, a magazine, means for advancing sheets into the magazine at one side, means movable toward and from the opposite side of the magazine for picking off successive single sheets, and means controlled by the extent of movement of the picking means for controlling the sheet advancing means.

18. In a sheet feeding apparatus, conveyor means for advancing sheets to a delivery point, movable means for picking off sheets at said de-

livery point, an electric motor for driving said conveyor means, a switch for the motor, and means constructed and arranged to operate said switch when the picking means moves beyond predetermined limits.

19. In a sheet feeding apparatus, conveyor means for advancing sheets to a delivery point, means for picking off successive sheets at said delivery point, said picking means being mounted for swinging movement toward and away from said delivery point, means for swinging said picking means, drive means for said conveyor means, a switch for said drive means, and means carried by said swinging means constructed and arranged to operate said switch when the picking means swings beyond predetermined limits.

20. In a sheet feeding apparatus, conveyor means for advancing sheets to a delivery point, means for picking off successive sheets at said delivery point, said picking means being mounted for swinging movement toward and away from said delivery point, means for swinging said picking means, drive means for said conveyor means, a tiltable mercury switch for said drive means, and means carried by said swinging means and constructed and arranged to cause said switch to be tilted when the picking means swings beyond predetermined limits.

21. In a sheet feeding apparatus, means for advancing sheets to a delivery point, means for gripping successive sheets at said delivery point, means for moving said gripping means toward and away from said delivery point, drive means for said sheet advancing means, a switch for said drive means, switch control means oscillatable toward and away from said gripper moving means, and means carried by said gripper moving means constructed and arranged to operate said switch control means when said gripping means moves beyond predetermined limits.

22. In a sheet feeding apparatus, conveyor means for feeding successive spaced packs of sheets into a magazine, an oscillatory picker for removing successive sheets from said magazine, means for advancing said conveyor, other means for advancing said conveyor at a greater rate of speed than that of said first-mentioned conveyor advancing means, means responsive to the extent of oscillatory movement of said picker for controlling said first-mentioned advancing conveyor means, and means responsive to the gaps between said packs for controlling the high speed conveyor advancing means.

23. In a sheet feeding apparatus, a magazine for holding a plurality of sheets on edge in a horizontal stack, said magazine comprising yieldable members for limiting the forward movement of sheets in said magazine, displaceable members against which the sheets in the magazine are urged by said yieldable members, and means for inserting additional sheets into said magazine by movement past said displaceable members.

24. In a sheet feeding apparatus, a sheet magazine, means for shifting the forward sheet of a stack in said magazine in a direction substantially normal to the face of said sheet to a position spaced apart from the stack, delivery means, and means engaging the edge of said sheet for moving said sheet in a direction substantially parallel to its face to present it to said delivery means.

25. In a sheet feeding apparatus, a sheet magazine, delivery means, reciprocatory means movable in one direction to shift the forward sheet of a stack in the magazine in a direction

substantially normal to the face of said sheet to a position spaced apart from the stack, and means carried by said reciprocatory means for engaging the edge of said sheet whereby the return movement of said reciprocatory means moves the sheet in a direction substantially parallel to its face to present it to the delivery means.

26. In a sheet feeding apparatus, a magazine for a stack of sheets, means movable between the forward sheet in said magazine and the remainder of the stack for separating said forward sheet from the stack, delivery means, and means carried by said separating means for engaging the edge of the separated sheet to transfer it to said delivery means.

27. In a sheet feeding apparatus, means for separating one side of the forward sheet of a stack from the remainder of the stack, a member constructed and arranged to complete the separation of the forward sheet from the stack, delivery means, and means associated with said member and movable thereby into engagement with the opposite edge of the sheet from the delivery means for transferring said sheet to said delivery means.

28. In a sheet feeding apparatus, means for bending one edge of a sheet in a stack away from the remainder of the stack, and means movable between said stack and said sheet and provided with a yieldable projection arranged to engage and complete the separation of said sheet from said stack.

29. In a sheet feeding apparatus, a sheet magazine, means including a suction member and a presser foot for bending one edge of the forward sheet in said magazine away from the stack therein, a separator for completing the separation of the forward sheet from the stack in the magazine, delivery means, and means carried by the separator for transferring said forward sheet to the delivery means.

30. In a sheet feeding apparatus, a sheet magazine, means for separating one side of the forward sheet in said magazine from the stack therein, means for successively removing individual sheets from said stack comprising a member reciprocable in a direction substantially parallel to the planes of the sheets in said stack and constructed and arranged to complete the separation of the forward sheet from the stack in the magazine, and an element carried by said member adapted to engage one edge of the foremost sheet in said stack to slide the same out of said magazine when said member is moved in one direction.

31. In a sheet feeding apparatus, a plurality of rotative carrier members having projections thereon and constructed and arranged to move a sheet to a delivery point, and means for advancing a sheet to said carrier members.

32. In a sheet feeding apparatus, a sheet magazine, means for removing a sheet from said magazine, a conveyor, a plurality of rotative carrier members, and means carried by said carrier members for engaging the sheet thereby to deliver it to said conveyor.

33. In a sheet feeding apparatus, a sheet magazine, a member for separating the forward sheet in said magazine from the stack therein, a sheet conveyor, a carrier wheel for delivering the sheet to said sheet conveyor, and means carried by the separating member for presenting said forward sheet to said carrier wheel.

34. In a sheet feeding apparatus, a sheet mag-

azine, means for separating the forward sheet in the magazine from the stack therein, a sheet conveyor, a carrier wheel having peripheral lugs and constructed and arranged to receive a sheet and to deliver it to said conveyor, and means carried by said separating means for presenting said forward sheet to the carrier wheel.

35. In a sheet feeding apparatus, a sheet magazine, a shuttle for separating the forward sheet in said magazine from the stack therein, means carried by said shuttle for sliding the leading sheet out of the magazine, a pair of carrier wheels having a plurality of peripheral sheet engaging members, and means for holding a sheet in position to be engaged by said sheet engaging members as the wheels are rotated.

36. In a sheet feeding apparatus, a sheet magazine, a shuttle for separating the forward sheet in said magazine from the stack therein, means carried by said shuttle for sliding the leading sheet out of the magazine, a carrier wheel, a second carrier wheel, and a conveyor chain passing about said second wheel and constructed and arranged to receive a sheet from said second wheel.

37. In a sheet feeding apparatus, means for picking a sheet from a stack, delivery means, means for transferring a sheet from said picking means to said delivery means, means for driving said picking and said transferring means, and means including a breakable member in said driving means constructed and arranged to stop said driving means when the picking or the transferring means jams.

38. In a sheet feeding apparatus, sheet advancing means, means including a gear for driving said sheet advancing means, a member rotatable with said gear, a breakable member connecting said gear and rotatable member, and means operable upon the breakage of said connecting member for stopping said driving means.

39. In a sheet feeding apparatus, sheet advancing means, means including a gear for driving said sheet advancing means, a member rotatable and coaxial with said gear, a shear pin connecting said gear and said member, means for moving said member axially away from said gear upon breakage of the shear pin, and means constructed and arranged to stop said driving means when the member moves axially away from the gear.

40. In a sheet feeding apparatus, a magazine, means for conveying packs of sheets to said magazine, a drive for said conveyor, means for picking a sheet from the magazine, delivery means, means for transferring a sheet from the picker means to the delivery means, means for driving the picker and the transferring means, a readily breakable member in one of said drive means, and means operable upon the breakage of said member for stopping both of said drive means.

41. In a sheet feeding apparatus, sheet advancing means, a switch for said means, delivery means, means including a breakable member for driving said delivery means, a switch for said driving means, means operable upon the breakage of said breakable member to open said switch for said delivery means, and a relay controlled by said delivery means switch for opening the switch controlling the sheet advancing means.

42. In a sheet feeding apparatus, sheet advancing means, means including a gear for driving said sheet advancing means, a member rotatable and coaxial with said gear, a shear pin

connecting said gear and said member, means for moving said member axially away from said gear upon breakage of the shear pin, a switch for said drive means, and a switch arm constructed and arranged to open said switch when said member moves axially away from the gear.

43. In a box making machine, a magazine for box blanks, a magazine for box cover blanks, means for picking a blank from the box blank magazine, means for picking a blank from the cover blank magazine, and means for preventing only one of said picking means from taking a blank from its respective magazine.

44. In a box making machine, a magazine for box blanks, a magazine for box cover blanks, means for picking a blank from the box blank magazine, means for picking a blank from the cover blank magazine, and means for causing one of said picking means to release its blank if the other picking means fails to pick a blank from its magazine.

45. In a box making machine, a magazine for box blanks, a magazine for box cover blanks, means including a suction member for picking a blank from the box magazines, means including a suction member for picking a blank from the cover blank means, and means for controlling the suction in said members, said means being constructed and arranged to render the suction in one member insufficient to hold a blank if the suction member of the other picking means fails to hold a blank.

46. In a box making machine, a magazine for box blanks, a magazine for box cover blanks, means including a suction member for picking a blank from the box magazine, means including a suction member for picking a blank from the cover blank means, means for initially evacuating the air from said suction members thereby to grip the forward sheets in said magazines, and means for reducing the rate of evacuation of air from said members after the initial contact of said members with their respective blanks.

47. In a box making machine, a magazine for box blanks, a magazine for box cover blanks, means including a suction member for picking a blank from the box magazine, means including a suction member for picking a blank from the cover blank magazine, and means for controlling the amount of suction of said members, said means being constructed and arranged to effect a relatively high initial suction and, subsequently, to reduce the amount of suction to a point where it is insufficient to hold a blank unless all the members are holding blanks.

48. In a box making machine, a magazine for box blanks, a magazine for box cover blanks, means including a suction member for picking a blank from the box magazine, means including a suction member for picking a blank from the cover blank magazine, a pump for withdrawing air from said members, all of said members being connected to said pump, and means for controlling the rate of evacuation by said pump, said means being constructed and arranged to reduce the rate of evacuation to a point where it will not maintain sufficient vacuum to hold a blank against one of said members unless all of said members are covered by blanks.

49. In a box making machine, a magazine for box blanks, a magazine for cover blanks, means including a suction member for picking a blank

from the box magazine, means including a suction member for picking a blank from the cover blank magazine, a pump for withdrawing air from said members, all of said members being connected to said pump, a valve, and a cam operative in timed relation to said picking means for controlling said valve, said cam being constructed and arranged to open said valve and subsequently to partially close it.

50. In a box making machine, a magazine for box blanks, a magazine for cover blanks, means including a suction member for picking a blank from the box magazine, means including a suction member for picking a blank from the cover blank magazine, a pump for withdrawing air from said members, all of said members being connected to said pump, and a valve mechanism constructed and arranged to open when said suction members engage the blanks in the magazines and thereafter partially to close, thereby to reduce the rate of withdrawal of air from said members to a point where it is insufficient to hold a blank unless all of said members are holding blanks.

51. In a sheet feeding apparatus, a magazine, means for picking a sheet from said magazine, means actuated by the picker means for registering the number of sheets picked thereby, and means controlled by the register means for preventing more than a predetermined number of sheets from being withdrawn from the magazine.

52. In a sheet feeding apparatus, a sheet magazine, means including a suction member for picking a sheet from said magazine, a valve by which the suction is governed, means controlled by the suction member for registering the number of sheets withdrawn from said magazine, and means controlled by said register means for actuating the valve.

53. In a sheet feeding apparatus, a magazine, means including a suction member for picking a sheet from said magazine, means controlled by the picker means for registering the number of sheets withdrawn from the magazine, a pump connected to said suction member and constructed and arranged intermittently to create a partial vacuum in said suction member, a valve for disconnecting said pump from said suction member, and electrical means constructed and arranged to close said valve when a predetermined number of sheets have been removed from the magazine.

54. In a sheet feeding apparatus, a magazine, means including a suction member for removing a sheet from said magazine, means for creating a partial vacuum in said suction member, a valve for controlling said vacuum creating means, electrical means for operating said valve, and means for controlling the valve operating means, said last-named means comprising a setting device and a counter for counting the operations of said removing means, said setting device and said counter being arranged to actuate said electrical means when their indications correspond.

55. In a sheet feeding apparatus, a sheet-conveyor, a magazine receiving sheets from the conveyor, means for picking a sheet out of said magazine, and means operative when a sheet moves out of its proper line of travel through the apparatus for shutting off the conveyor and the picker means.

56. In a sheet feeding apparatus, a sheet-conveyor, a magazine receiving sheets from the conveyor, means for picking the forward sheets from said magazine, delivery means, means for trans-

ferring a sheet from said picking means to said delivery means, and means operated by the jamming of a sheet in said magazine for shutting off the conveying, picking and transferring means.

57. In a sheet feeding apparatus, a magazine for holding sheets in a horizontal stack, means for moving a sheet out of said magazine, a finger adjacent to said magazine and out of the normal path of travel of a sheet out of said magazine, and means controlled by said finger for stopping the machine, said finger being constructed and arranged to be actuated by a sheet moving out of its normal line of travel from the magazine.

58. In sheet feeding apparatus, conveyors for two stacks of sheets, a magazine into which the sheets of each stack are advanced by the corresponding conveyor, a movable suction device for drawing forward a portion of the leading sheet in each magazine, a separator movable between such leading sheet and the succeeding sheet in each magazine, high and low speed motors for operating each conveyor, a main motor for operating the suction devices and the separators of both magazines, means made effective upon failure of a suction device to act properly upon a sheet in one magazine to render ineffective the suction device at the other magazine, means acting when a separator encounters undue resistance during engagement with a sheet for disconnecting said separator from the main motor and for stopping said main motor and the conveyor motors, means acting when a sheet is carried out of the desired path by a separator for stopping the motors, and means controlled by the number of sheets acted upon by the suction devices for shutting off the suction from said devices.

59. In sheet feeding apparatus, conveyors for two stacks of sheets, a magazine into which the sheets of each stack are advanced by the corresponding conveyor, a movable suction device for drawing forward a portion of the leading sheet in each magazine, a line through which suction in the devices is created, a separator movable between the leading sheet and the succeeding sheet in each magazine, high and low speed motors for operating each conveyor, a main motor for operating the suction devices and the separators of both magazines, an electro-magnetic switch for governing the circuit of the main motor, a valve in the suction line, means for partially closing the valve periodically, means acting when a separator encounters undue resistance during engagement with a sheet for disconnecting said separator from the main motor, a contact device controlling the circuit of the electro-magnetic switch winding and opened by the disconnecting means, a contact device controlling the circuit of said electro-magnetic switch winding and opened by a sheet carried out of the desired path by the separator, a relay having its winding in circuit with the contacts of the main switch and controlling the conveyor motors, a second valve in the suction line, a solenoid having the circuit of its winding controlled by the relay and its plunger connected to the second valve, and a counter actuated by the blanks and having a contact device controlling the circuit of the solenoid winding.

60. In sheet-feeding apparatus, a conveyor for a plurality of packs of sheets, and pack-engaging members mounted upon the conveyor to trav-

el therewith and also to move bodily upon the conveyor into and out of the path of the packs.

61. In sheet-feeding apparatus, a magazine, a conveyor for a plurality of packs of sheets delivering to the magazine, and pack-engaging members mounted upon the conveyor to travel therewith and also to move bodily upon the conveyor out of the path of the packs and in a direction substantially parallel to the sheets in the magazine.

62. In sheet-feeding apparatus, a conveyor for a plurality of packs of sheets, mounting members included in the conveyor, and pack-engaging members slidable through the mounting members.

63. In sheet-feeding apparatus, a conveyor for a plurality of packs of sheets, pack-engaging members mounted upon the conveyor to travel therewith and also to move upon the conveyor into and out of the path of the packs, and means for supporting the engaging members at different levels.

64. In sheet-feeding apparatus, a conveyor for a plurality of packs of sheets, pack-engaging members mounted upon the conveyor to travel therewith and also to move upon the conveyor into and out of the path of the packs, means for supporting the engaging members at upper and lower levels, and means for shifting the engaging members upon the conveyor from one level to another.

65. In sheet-feeding apparatus, a conveyor for a plurality of packs of sheets, pack-engaging members mounted upon the conveyor to travel therewith and also to move upon the conveyor into and out of the path of the packs, means for supporting the engaging members at upper and lower levels, and means for elevating the engaging members from the lower level to the upper and for forcing down said engaging members from the upper level to the lower.

66. In sheet-feeding apparatus, a conveyor for a plurality of packs of sheets, pack-engaging members mounted upon the conveyor to travel therewith and also to move upon the conveyor into and out of the path of the packs, means for supporting the engaging members at upper and lower levels, and a movable shifting member acting simultaneously upon the engaging members at the opposite ends of the conveyor.

67. In sheet-feeding apparatus, a support for a plurality of packs of sheets, conveyors traveling at opposite sides of the support, pack-separators movable upon the conveyors, and separator-supports situated at different levels.

68. In sheet-feeding apparatus, a magazine, a support for a plurality of packs of sheets, conveyors traveling at opposite sides of the support and delivering to the magazine, pack-separators movable upon the conveyors upon arrival at the magazine, and separator-supports situated at different levels.

69. In sheet-feeding apparatus, a support for a plurality of packs of sheets, conveyors traveling below and at opposite sides of the support about vertical axes, and transversely aligned separators extending upwardly from the conveyors for engagement with the packs upon the support.

70. In sheet-feeding apparatus, a support for a plurality of packs of sheets, conveyors traveling at opposite sides of the support about vertical axes, transversely aligned separators for the packs movable upon the conveyors, and upper and lower supports for the separators situated at opposite sides of the pack-support.

71. In sheet-feeding apparatus, a support for a plurality of packs of sheets, conveyors traveling at opposite sides of the support about vertical axes, transversely alined separators for the packs carried by the conveyors, upper and lower supports for the separators situated at opposite sides of the pack-support, and means acting upon the separators of both conveyors for shifting them from one of their supports to the other.

72. In sheet-feeding apparatus, a support for a plurality of packs of sheets, conveyors traveling at opposite sides of the support about vertical axes, transversely alined separators for the packs carried by the conveyors, and means for simultaneously elevating the separators of both conveyors from the lower level to the upper and for forcing down said separators from the upper level to the lower.

73. In combination, a pack-supporting table, a conveyor-chain traveling about vertical axes at each side of the table, pack-separators movable upon the chains, and upper and lower tracks upon which the separators travel.

74. In combination, a pack-supporting table, a

conveyor-chain traveling about vertical axes at each side of the table, pack-separators movable upon the chains, upper and lower tracks upon which the separators travel, and a movable member provided with means for successively acting upon the separators of both conveyors for shifting said separators upon the chains from one of their tracks to another.

75. In combination, a pack-supporting table, a conveyor-chain traveling about vertical axes at each side of the table, pack-separators movable upon the chains, upper and lower tracks upon which the separators travel, and a lever fulcrumed beneath the table and provided with means at its opposite extremities for shifting the separators of both conveyors between the tracks.

76. The combination with a pack-supporting table, of two conveyor-chains traveling in cooperation with the table one above the other about vertical axes, guide members included in the chains in vertically registering pairs, and pack-separators movable through the guide members.

CUTLER D. KNOWLTON.
